UNITED STATES PATENT OFFICE.

STEPHEN W. MCGRATH, OF CINCINNATI, OHIO.

METAL-FRAME SCREEN.

947,838.

Specification of Letters Patent.

Patented Feb. 1, 1910.

Application filed October 3, 1908. Serial No. 455,968.

To all whom it may concern:

Be it known that I, STEPHEN W. MCGRATH, a citizen of the United States, residing at Cincinnati, in the county of Hamilton and 5 State of Ohio, have invented certain new and useful Improvements in Metal - Frame Screens, of which the following is a specification.

My invention relates to metal - frame 10 screens of the box-frame type shown and described in Letters Patent of the United States No. 767,487, granted W. E. Monroe, August 16, 1904, and its object is to improve upon the screen shown and described in that 15 patent, and the invention will be readily understood from the following description and claims and from the drawings, in which latter:

Figure 1 is a front elevation of a metal- 20 frame window-screen embodying my invention, the same being partly broken away and partly in section for better illustration of parts, also showing the friction-spring at the side of the frame in assumed position in 25 dotted lines, the window-frame being also indicated in dotted lines and broken away. Fig. 2 is a perspective view of one of the corners of the frame in separated relation. Fig. 3 is a cross section of my improved de- 30 vice taken on the line 3—3 of Fig. 1 but showing screen-cloths at both sides of the screen. Fig. 4 is a cross section of the parts shown in Fig. 3, taken on a similar line, but showing the same in separated relation. Fig. 35 5 is a detail in cross section on the line 5 of Fig. 1, showing the frame in assembled relation with the inner reinforce corner and the outer corner in place. Fig. 6 is a detail in edge relation showing the friction-spring 40 in place. Fig. 7 is a vertical section of the same on the line 7—7 of Fig. 6, and Fig. 8 is a cross section of the same on the line 8—8 of Fig. 6.

The stiles 1 and rails 2 of the screen each 45 comprise an inner frame-member 3 and an outer frame-member 4, both of which are of substantial U-shaped channel form in cross section, with the walls of the channels ex- 50 tending in directions substantially parallel with the screen-cloth when assembled for forming a box-frame screen of the character of that shown and described in the aforesaid patent, in which the walls of the frame- 55 members are substantially parallel to the plane of the screen-cloth.

The inner frame-member comprises a base

5 and walls 6 6, the latter extending outwardly from the respective sides of the base.

The outer frame-member comprises a base 7 and walls 8 8, the latter extending inwardly from the respective sides of the base. The walls of these frame-members preferably extend substantially radial of the screen when assembled.

Outwardly extending beads 9 9 are be- 65 tween the base 5 and respective walls 6 of the inner frame-member, being formed up from the sheet metal of which the inner frame-member is composed.

Channels 10 are thus formed, in the ends 70 of which, at the corners of the screen, limbs 11 11 of inner reinforce corner pieces 12 are received. These reinforce corner-pieces are preferably formed of metal which fits the channels and which is bent for forming the 75 limbs, which are substantially at right angles to each other. The limbs are received in the channels of the inner frame-members for reinforcing the screen at the corner thereof. The outer ends of the walls 6 are 80 preferably bent inwardly as shown at 13, being preferably bent back upon the walls and forming strengthening edges for the same.

The walls 8 of the outer frame-members 85 may be provided with inwardly projecting beads 16 adjacent their bases. These beads serve the purpose of strengthening the outer members.

The inner frame-members are preferably 90 mitered at the corners, as shown at 21, and the outer frame-members are preferably mi- 95 tered at the corners, as shown at 22. An outer corner-piece 23, which preferably com- 100 prises a base 24 and walls 25 having exten- 105 sions 26, covers the joint at each of the cor- 110 ners of the screen. The respective walls and extensions of the outer corner-piece are pro- 115 vided with inwardly extending beads 27. The beads 27 are received within the outer 100 grooves of the beads 16. Rivets 29 pass through the outer corner-piece and the walls of the outer and inner frame-members for 105 securing the parts together, recesses 30 31 32 being formed respectively in the outer cor- 110 ner-piece, and in the walls of the outer and inner frame-members for accommodating the rivet-heads, it being understood that the screen-cloth, shown at 33, will have been se- 115 cured in place before the frame is riveted together, and, if desired, one or more rivets, as shown at 34, may be passed through the

walls of the outer and inner frame-members intermediate of the corners for securing the parts together.

In assembling the screen, the inner reinforce corner-pieces are received in the ends of the channels 10 at the respective ends of the stiles and rails for forming the corners, these inner frame-members respectively being preferably a one-piece structure for the 10 respective stiles and rails, thereby forming an inner frame for the screen. The walls of the inner frame-members preferably diverge from each other slightly as indicated in Fig. 4. The screen-cloth is received about the 15 outer ends of these diverging walls and bent inwardly as shown at 35. The inwardly bent end of the screen-cloth is received within the channel of the inner frame-member if desired. There may be a screen-cloth on 20 but one side of the inner frame as shown at 33 and there may be an additional screen-cloth 36 at the other side of the inner frame, the inner edges 37 of which are bent over the other wall of the inner frame-member 25 and received within the channels of said frame-members, the said screen-cloth 36 being preferably a protecting cloth of wider mesh than the screen cloth 33. When now the outer frame-members are forced over the 30 inner frame-members, the walls of the latter which have been in flexed relation, are reflexed into parallelism with the screen-cloth, thereby stretching the screen-cloth between the frame-members at the opposite ends of 35 the screen. The screen-cloth is firmly clasped between the walls of the respective inner and outer members. The inner edges of the walls of the outer frame-members clamp the screen-cloth between themselves 40 and the beads of the inner frame-members, over which latter the screen-cloth is curled. The mouths 38 39 of the respective inner and outer frame-members are presented in directions substantially parallel with the 45 screen-cloth when the screen is assembled. When the outer-frame-members have been received about the inner frame-members and the screen-cloth thereon, the outer corner-pieces are secured in place as hereinbefore 50 described.

41 41 represent friction-springs, one or more of which may be employed. These springs are shown as leaf-springs and are respectively received through slits 42 43 44 55 in the base of one of the outer frame-members, whereby an outer strap 45 and an inner strap 46 are formed, between which the friction-spring is received, the heel 47 of said spring being received under the base of said outer frame-member. The said friction-spring extends outwardly away from the screen-cloth in a curve whose convexity is presented toward the side of the screen-frame. In other words, the side of said screen-frame 60 65 is tangent to said curve. Said spring is

preferably provided with an inward extension 48, which projects through an aperture 49 in the base of said outer frame-member, there being a toe 50 at the inner end of said extension inside said outer frame-member, which is adapted to contact the inner face of the base of said outer frame-member, thereby limiting the outward projection of said spring and holding said spring in place under tension, the tension of said spring 75 locking the same in place in the slits and avoiding necessity of other fastening means. When said screen is in place in the window-frame, indicated in dotted lines at 51, which forms a guide-way for the screen, the outer end of said spring is forced toward the frame of the screen and thereby exerts additional friction against longitudinal movement of the spring at the walls of said slits. If it is desired to release said spring this 80 may be easily done by forcing the inner end of the inward extension 48 lengthwise of the spring for releasing the toe 50 from contact with the inner face of the outer frame-member, thereby permitting it to pass 85 through the aperture 49. When forced inwardly, the extension is received within the channels of the frame-members. The side of the screen-frame opposite the spring may be provided with a handle 52 and a suitable 90 raising handle 53 may also be provided.

Having thus fully described my invention, what I claim as new and desire to secure by Letters Patent is:

1. In a metal-frame screen of the character described, the combination of an inner frame-member, an outer frame-member, and a screen-cloth, said frame-members comprising opposed stile and rail lengths, the said lengths of said members being of substantial U-shaped channel form in cross-section comprising a base and side walls having mouths presented toward each other and substantially parallel to the plane of said screen-cloth, the said stile and rail lengths of said inner frame-member each having an outwardly projecting bead extending longitudinally thereof adjacent its base, said screen-cloth being curled over said beads and clamped between the adjacent side walls at one of the sides of said frame-members, said screen-cloth being stretched between the beads of opposed lengths of said inner frame-member so that the plane of said screen-cloth between said beads will be coincident with the outer faces of the said beads for locating said screen-cloth between said beads of said opposed lengths of said inner frame-member to one side of the frame of said screen, substantially as described.

2. In a metal-frame screen of the character described, the combination of an outer frame-member, an inner frame-member, and a screen-cloth, said frame-members comprising opposed stile and rail lengths, the said

- lengths of said frame-members being of substantial channel-form in cross-section comprising a base and side walls and having mouths presented toward each other, the said 5 stile and rail lengths of said inner frame-member having outwardly projecting beads and the said stile and rail lengths of said outer frame-member having inwardly projecting beads, the said beads extending longitudinally of and adjacent to the bases of the 10 lengths on which the same are located, the said beads being respectively located between the bases of the lengths of that frame-member on which the same are located and the 15 side walls of the lengths of the other of said frame-members, and said screen-cloth being located between the free edges of said side-walls and beads at one of the sides of said frame-members and stretched between the 20 beads of opposed stile and rail lengths of said inner frame-member, the said stretched portion of said screen-cloth extending outwardly beyond said beads and side-walls, substantially as described. 25
3. In a metal-frame screen of the character described, the combination of outer and inner frame-members, and a screen-cloth, said inner and outer frame-members comprising opposed stile and rail lengths, the 30 said lengths of said frame-members being each of substantial channel-form in cross-section comprising a base and opposed side-walls, said opposed side-walls being at the respective sides of said bases, the said stile and 35 rail lengths of said inner frame-member having outwardly projecting beads adjacent their bases and the said stile and rail lengths of said outer frame-member having inwardly projecting beads adjacent their bases, the 40 said beads on one of said frame-members being in the lateral planes of the side-walls of the other of said frame-members, said screen-cloth being received between said opposed side-walls and beads at one of the 45 sides of said frame-members and stretched between the beads of opposed stile and rail lengths of said inner frame-member for locating the plane of said stretched portion of said screen-cloth when extended to one side 50 of said inner frame-member outside said inner frame-member, substantially as described. 55
4. A metal-frame screen of the character described comprising in combination stiles and rails, having joints at the corners of said screen, said stiles and rails embracing opposed inner and outer frame-members, a screen-cloth, said frame-members being of substantial channel form comprising a base 60 and opposed side-walls, said opposed side-walls being at the respective sides of the bases, said opposed side-walls at one of said sides being spaced from said opposed side-walls at the other of said sides, said inner 65 frame-member being provided with an out- 70 wardly projecting bead extending longitudinally thereof and bent from the metal of which said inner frame-member is composed for forming an inner channel, inner corner pieces respectively having limbs at substantial right-angles to each other received by said channels in said stiles and rails at the respective corners of said screen, and outer corner-pieces received over said joints at 75 said corners. 75
5. In a metal-frame screen of the character described, the combination of stiles and rails comprising inner and outer frame-members of channel form comprising a base and side-walls spaced apart projecting from said 80 base, a screen-cloth received between the side-walls of said frame-members, said side-walls extending in planes substantially parallel with the plane of said screen-cloth, each of said inner frame-members having a bead 85 at each side of its base formed therefrom for forming an inner channel, and inner reinforce corner-pieces respectively having limbs at substantially right angles to each other received in said channels of said 90 respective stiles and rails at the corners of the screen, substantially as described. 90
6. In a metal-frame screen, the combination of a sheet-metal frame-member provided with slits for forming straps, and a 95 leaf friction-spring, one end of which is received by said slits for being received alternately under and above said straps of said sheet-metal frame-member at different points, the other end of said leaf friction-spring extending outwardly on a curve whose convexity is presented toward said frame-member and acting when flexed out of normal position to bind said first-named end of said spring against said straps. 100 105
7. In a metal-frame screen, the combination of a sheet-metal frame-member provided with slits for forming straps, a leaf friction-spring, one end of which is received by said slits for being received under and above said straps of said sheet-metal frame-member at different points, the other end of said leaf friction-spring extending outwardly on a curve whose convexity is presented toward said frame-member and acting when flexed out of normal position to bind said first-named end of said spring against said straps, said leaf-friction-spring having an inward extension and said metal frame-member having an aperture through which said extension is received, and limiting means between said extension and frame-member for limiting the retraction of said outwardly extending end of said spring from said frame-member. 110 115 120 125
8. In a metal-frame screen, the combination of a sheet-metal frame-member and a leaf friction-spring adapted to contact the slideway for said screen, said frame member being provided with slits through which one 130

4

end of said friction-spring is received, the other end of said friction-spring being bent outwardly from said slits and being provided with an extension, the said frame-member being provided with an aperture for receiving said extension when said spring is flexed out of normal position by contact with said slide-way.

9. In a metal-frame screen, the combination, with a screen-cloth, of a hollow metal-frame embracing inner and outer frame-members having bases and opposed side-walls at the respective sides of said bases, said side-walls being substantially parallel to the plane of said screen-cloth, a friction-spring secured at one end to said frame and adapted to contact the guideway of said screen, the other end of said friction-spring

extending outwardly from said frame, said friction-spring having an inner extension at 20 said other end, the base of one of said outer members having an aperture through which said extension is received between said opposed side-walls at the respective sides of said bases, said extension having a hook in 25 its inner end received through said aperture, and said hook contacting the inside of said frame for limiting the outward movement of said spring, substantially as described.

In testimony whereof I have subscribed 30 my name hereto in the presence of two subscribing witnesses.

STEPHEN W. McGRATH.
